UNITED STATES PATENT OFFICE.

HARRY H. BATES, OF JOLIET, ILLINOIS.

TRACTOR.

1,295,673.

Specification of Letters Patent. Patented Feb. 25, 1919.

Application filed September 7, 1916. Serial No. 118,855.

To all whom it may concern:

Be it known that I, HARRY H. BATES, a citizen of the United States, residing at Joliet, in the county of Will and State of Illinois, have invented certain new and useful Improvements in Tractors, of which the following is a specification.

The present invention has to do with tractors and particularly with devices of this kind which are specially well adapted for use on the farm. It will, however, appear from a detailed study of the construction to be presently disclosed that the features of the present invention are in no wise limited to use in tractors for this particular class of service.

It is very desirable in machines of this type to make provision for the turning of very sharp angles, so as to give great flexibility in the steering function. Therefore, one of the objects of the invention is to provide a construction by means of which a very sharp angle can be turned with a minimum effort on the part of the operator.

It is also very desirable in machines of this type to make provision for easy riding over rough ground. This is especially desirable in case of machines of this type which are to be used in connection with the cultivation of fields which have already been plowed, although, of course, the desirability of securing smooth riding is also present in any case where the machine is traveling over rough ground. Therefore, another object of the invention is to provide a construction such that will ride over inequalities in the surface of the ground with a minimum amount of movement of the body of the vehicle in a vertical direction. More particularly, this feature of the invention has reference to a construction in which use is made of the equalizing principle of a three point suspension, so that the vertical movement or oscillation of the frame of the machine will be correspondingly reduced.

Another feature of the invention has to do with the performance of the equalizing function in the forward portion of the machine as distinguished from the rear portion thereof. This will enable the machine to approach and ride onto an elevation or depression in the surface of the ground with a minimum amount of effort.

Other objects and uses of the invention will appear from a detailed description of the same which consists in the features of

construction and combinations of parts hereinabove described and claimed.

Referring to the drawings:

Figure 1 shows a plan view of a tractor embodying the features of the present invention;

Fig. 2 shows a side elevation of the machine illustrated in Fig. 1;

Fig. 3 shows a front elevation of the machine illustrated in Fig. 1; and

Fig. 4 shows in enlarged detail a fragmentary view of the lower portion of the radiator, the front portion of the frame of the machine, and the equalizer frame.

Before proceeding with the detailed description of the construction illustrated in the drawings, I wish to point out first that I have shown the features of the present invention as being applied to a tractor of the general type which is shown in Letters Patent of the United States, No. 1,179,066, which was issued to me April 11, 1916. Certain of the features of construction disclosed in this case are also shown in my co-pending applications for Letters Patent of the United States on improvements in tractors, Serial No. 37,512, which was filed July 1, 1915, and issued August 29, 1916, as Patent No. 1,196,507, and Serial No. 49,260, which was filed September 7, 1915, as well as my application for Letters Patent of the United States on improvements in control mechanism for tractors and the like, Serial No. 66,520, which was filed December 13, 1915, issued June 12, 1917, as Patent No. 1,229,865. I desire to state at this point, however, that while the features of the present invention are herein illustrated as being applied to tractors of the types disclosed in the said various applications and issued Letters Patent, still I do not by such illustration limit myself to their application to such particular forms of tractor, except as I may hereafter do so in the claims.

Bearing the foregoing facts in mind, I will now describe in detail the particular construction illustrated in the drawings. The frame of the machine comprises generally the side rails 5 and 6 which are connected together at various points throughout their length so as to provide a substantial framework. These rails may be connected together for this purpose in any suitable manner, as by means of the bed of the engine 7, the bed of the change speed mechanism 8, the bracket 9, etc. Connected to the

bottom portion of each of the rails 5 and 6 is a downwardly extending bracket 10, within which is journaled a main driving wheel 11. Suitable operative connections 5 are provided from the engine 7 through the change speed mechanism 8 to the driving wheel 11, said connections being under control of the operator as by means of the hand wheel 12. This hand wheel is illustrated as comprising a portion of the rearwardly extending control mechanism 13. Said control mechanism also includes a hand wheel 14, to which is operatively connected a sprocket 15. The driving wheel 11 is shown as driving a caterpillar chain 16, which chain rides over an end pulley 17 journaled with respect to the forward ends of the arms 18. Said arms 18 are pivoted to the brackets 10 at the points 19, so that 10 they may oscillate up and down on said pivotal points. Springs within the boxes 20 exert a downward thrust on the arms 18 with respect to the frame of the machine, thereby transmitting a portion of the load 15 to the caterpillar 16 through the medium of the arms 18.

Rearwardly extending from the arms 18 are the draft rods 21, the forward ends of which are pivoted to the arms 18 at the 20 points 22. The rear ends of the draft rods 21 are connected together and supported by the vertical draw bar 23. The upper end of said draw bar is connected to the main frame of the machine by a pivotal point 24. The arrangement is such that the draft exerted by the lower portion of the bar 23 is transmitted through the draft rods 21 on lines which pass through the pivotal points 22 and beneath the pivotal points 19, so that 25 the pull or draft in itself tends to swing the arms 18 downwardly, thus increasing the amount of pressure on the caterpillar 16. Certain of the constructions thus far described are illustrated and described in detail in one or the other of the aforementioned Letters Patent and applications for Letters Patent of the United States.

During the travel of the tractor over rough ground, the forward ends of the arms 18 will oscillate up and down, thus also carrying the forward ends of the draft rods 21 up and down. These draft rods, in the construction illustrated herein, pass beneath the journals 25 of the driving wheel 11, and in 55 case of excessive oscillation of the front ends of the said draft rods, their central portions will be carried up into engagement with the said journals. In order to permit the draft rods to bend or deflect under these 60 conditions, I have shown them as being provided with the joints or hinges 26 particularly shown in Fig. 2 of the drawings in this case.

In carrying into effect the features of the 65 present invention, I provide what may be

termed an equalizer frame in the front portion of the machine. Said equalizer frame is pivoted, or at any rate is movable, with respect to the main frame of the machine and carries one or more ground wheels at 70 such points that the rising and falling of said ground wheels will not be transmitted in full degree to the frame of the machine. In the particular construction illustrated in the drawings, this equalizer frame is of 75 U-shaped construction, being designated in its entirety by the numeral 27. It is conveniently built up from a pair of angle or channel bars 28 and 29 which are rigidly joined together in any suitable manner. In 80 the construction illustrated, such joining together is effected by means of the journal brackets 30, 31, and 32, as well as various cross pieces 33 and 34.

The equalizer frame is pivoted to the 85 main frame in such a manner that, during the travel of the machine over rough ground, the equalizer frame may oscillate with respect to the main frame. The pivoting illustrated is effected by means of the brackets 90 35 and 36 which are carried inwardly to points adjacent to the side bars 5 and 6, to which side bars the said brackets are journaled or pivoted by the brackets 37 and 38, so that the equalizer frame may oscillate 95 about the horizontal transverse axis 39 best shown in Figs. 2 and 3. In the particular arrangement illustrated, the equalizer frame carries three wheels, namely, a center wheel 40 and side wheels 41 and 42. Also, in the 100 particular arrangement illustrated all of these wheels are journaled so that they may turn about substantially vertical axes during the steering function. This journaling is effected by means of the studs 43, 44, and 105 45, which extend upwardly through and are journaled in the bearing plates or brackets 30, 31, and 32.

Reference to Figs. 1 and 2 shows that the 110 wheel 40 rides in advance of the horizontal axis 39, whereas the wheels 41 and 42 ride behind said axis. Consequently the load of the forward end of the tractor frame will be transmitted to the ground through the medium of all three of said wheels. 115 Furthermore, any rising or falling of the wheel 40 with respect to the wheels 41 and 42 will be accompanied by a very much smaller degree of vertical movement of the front portion of the tractor frame, the ratio 120 between the movement of the front portion of the tractor frame as compared to the movement of the wheel 40 being measured substantially as the ratio of the distance from the wheels 41 and 42 to the axis 39 125 as compared to the distance from said wheels to the wheel 40. In the particular construction illustrated, this ratio is approximately 1 to 3.

The wheel 40 will ordinarily be used dur-

ing the steering operation, and the wheels 41 and 42 may or may not be used for a similar purpose. I will state that in the particular construction illustrated, the wheels 5 40, 41, and 42 are connected together in such a manner that they all operate during the steering function, but this is done largely as a matter of convenience, and one or more of said wheels may be treated and used 10 in many cases as trailers or simply caster wheels. In fact it will be observed from an examination of particularly Fig. 2 that the wheels 41 and 42 are castered backwardly with respect to the journals 44 and 45, so 15 that they will always trail and follow in the direction of travel.

In the particular construction illustrated, the steering function is performed by the wheel 14 which is operatively connected to 20 the sprocket 15 as has been previously explained. Extending forwardly along the main frame of the machine is the rod 46 journaled at the point 47. The said rod has the sprocket 48 which is connected to 25 the sprocket 15 by means of a chain 49. Journaled on the equalizer frame 27 is another rod 50 which is journaled at the points 51 and 52. The rods 50 and 46 are connected together through the medium of a 30 universal joint 53 and a sliding connection 54. Consequently the rods 46 and 50 are always operatively connected together even during the oscillation of the equalizer frame.

On the rod 50 is a beveled pinion 55 meshing with the beveled gear 56 on the upper end of the stub shaft 57. The said stub shaft is journaled in the equalizer frame, and at its lower end it carries a sprocket wheel 58. The stud 43 carries a sprocket 40 wheel 59 connected to the sprocket wheel 58 by means of a chain 60, so that the rotation of the rod 46 will serve to turn the wheel 40 for the steering function.

When the wheels 41 and 42 are also to be 45 used during the steering function, the studs 44 and 45 will be connected to the stud 43 or to the steering mechanism in a proper manner. It will be observed that, in order to secure a perfect turning operation, the 50 amount of turn of each of the wheels 40, 41 and 42 should be different from the amount of turn of the other of said wheels, so that all of said wheels will have a tendency to turn the tractor about the same 55 center of turn at one side or the other depending upon the direction of turn. In other words, the several steering wheels should be equalized during the steering function. I have, therefore, illustrated an arrangement whereby this result may be accomplished. This arrangement includes the bell crank 61 and 62 pivoted to the brackets 33 and 34 respectively. The stud 43 carries the lever arm 63 which is connected to the bell cranks 61 and 62 by the links 64 and 65

respectively. The studs 44 and 45 carry the lever arms 66 and 67 respectively which are connected to the other arms of the said bell cranks by means of the links 68 and 69 respectively.

70

It will be evident that, with this arrangement, the wheels 41 and 42 will be turned for the steering function simultaneously with the wheel 40. It was previously explained that it is desirable to so relate the turning 75 of the wheels 41 and 42 to the turning of the wheel 40 that all of said wheels will tend to turn the tractor about the same center, so that the turning operation will be performed in the easiest manner possible. 80 When turning toward the right hand, looking in the direction of travel, the wheel 41 should be turned at the sharpest angle, the wheel 40 at a slightly less angle, and the wheel 42 at a still smaller angle, in order 85 to cause all of said wheels to effect the turning tendency on the same center.

Conversely, when turning toward the left hand, looking in the direction of travel, the wheel 42 should be turned a greater amount 90 than the wheel 40, and the wheel 40 should be turned a greater amount than the wheel 41. These results I secure by the use of the bell cranks 61 and 62, in conjunction with the crank arms 66 and 67. By properly proportioning the various arms of the bell cranks as compared to the crank arms 66 and 67, and by setting the arms of the bell cranks at the proper angles, the aforementioned compensation may be secured 95 100 when turning in either direction.

In riding over obstructions or inequalities in the surface of the ground, the equalizer frame will tilt or oscillate with respect to the main frame on the horizontal transverse 105 axis 39 in the manner which has been previously explained. In case one of the wheels of the equalizer frame should strike an unusually high obstruction, it might occur that the equalizer frame would be tilted so as to imperil the stability of the entire machine. In such case there would be a tendency for the machine to turn over, the equalizer frame doubling up as it were by swinging 110 on the axis 39. I have, therefore, provided the chains 70 and 71 which connect the forward portions of the main frame to the arms of the equalizer frame. In the construction illustrated, the outer ends of said chains connect to brackets 72 and 73 carried 115 by the angle bar 29 of the equalizer frame, and the inner ends of said chains are connected to brackets 74 and 75. These brackets 74 and 75 are connected to the forward ends of the rails 5 and 6 respectively. The 120 brackets 74 and 75 also serve as a convenient mounting for a radiator. The lower portion of the radiator seats down between said brackets and the radiator is supported by them, springs 76 and 77 serving to cushion 125 130

the radiator and take up vibrations during the travel of the machine.

While I have herein shown and described only a single embodiment of the features of my invention, still it will be understood that I do not limit myself to the said embodiment except as I may do so in the claims.

I claim:

1. In a machine of the class described, the combination with a main frame, of an equalizer frame of U-shaped formation in the forward portion of the machine, a pivotal connection between the arms of said equalizer frame and the forward portion of the main frame permitting the equalizer frame to oscillate with respect to the main frame about a horizontal transverse axis, a steering wheel pivotally mounted with respect to the central portion of the equalizer frame, a steering wheel pivotally mounted with respect to the end of each arm of the equalizer frame, the aforementioned pivotal connection between the main frame and the equalizer frame being rearward of the first mentioned steering wheel and forward of the second mentioned steering wheels, and means for simultaneously turning all of the steering wheels to perform the steering function.
2. In a machine of the class described, the combination with a main frame, of an equalizer frame pivoted to the main frame to oscillate about a horizontal transverse axis with respect to the main frame, three steering wheels pivotally mounted on the equalizer frame at points in advance of and behind the aforementioned pivotal connections between the main frame and the equalizer frame, and means for turning all of the steering wheels simultaneously in the steering function.
3. In a machine of the class described, the combination with a main frame having driving means in its rear portion, of an equalizer frame pivoted to the main frame to oscillate about a horizontal transverse axis, a steering wheel pivoted to the equalizer frame centrally with respect to the axis of the machine, and other wheels pivoted to the equalizer frame one on each side of the main frame, the steering wheel and the last men-

tioned wheels being on opposite sides of the aforementioned transverse horizontal axis.

4. In a machine of the class described, the combination with a main frame having driving means in its rear portion, of an equalizer frame pivoted thereto and comprising a self-contained truck, a steering wheel in said truck, and suitable supporting wheels in the truck on the opposite side of the pivotal mounting.

5. In a machine of the class described, the combination of a main frame having driving means in its rear portion, of a self-contained truck, a pivotal connection between said truck and the main frame permitting oscillation about a transverse horizontal axis, a steering wheel pivotally mounted centrally of the truck and in its forward portion, and supporting wheels pivotally mounted at each side of the truck, and behind the line of oscillation of the truck with respect to the main frame.

6. In a machine of the class described, the combination with a main frame, of driving means in the rear portion of the same, a self-contained truck adjacent to the forward portion of the main frame, a pivotal connection between the main frame and said truck, a steering wheel in the truck centrally with respect to the main frame, and suitable supporting wheels at the sides of the truck, and behind the pivotal connection between the main frame and the truck.

7. In a machine of the class described, the combination with a main frame, of a supporting and driving device in the rear portion of the same, a steering wheel in the forward portion of the same and centrally thereof, and a supporting wheel on each side of the machine, said supporting wheels and the steering wheel being pivotally connected to the main frame to oscillate about a horizontal transverse axis, which axis lies between the supporting wheels and the steering wheel.

HARRY H. BATES.
